UNITED STATES PATENT OFFICE.

WILLIAM HENRY ILLINGWORTH, OF HALIFAX, ENGLAND.

ELECTRICAL CIRCUIT BREAKER.

Application filed October 27, 1920. Serial No. 419,834.

To all whom it may concern:

Be it known that I, WILLIAM HENRY ILLINGWORTH, a subject of the King of Great Britain, residing at 1 Ruskin Terrace, Lee 5 Mount, Halifax, in the county of York, England, have invented certain new and useful Improvements in Electrical Circuit Breakers, of which the following is a specification.

This invention relates primarily to a carrier or holder which can be used in conjunction with a mercury cutout or circuit breaker, such as that which is described in my prior United States Patent No. 1,316,095, 10 granted Sept. 16, 1919, or in conjunction with a wire fuse.

In the accompanying drawings:—

Figure 1, is a vertical section and Figure 2 a plan of a cut-out, or circuit breaker constructed in accordance with this invention.

Figure 3 is a detached view of the core.

Figure 4 shows a modified form of cut-out, or circuit breaker partly in section and partly in elevation.

Figure 5 is a plan of the device shown in Figure 4.

Fig. 5^a is a similar view illustrating a slight modification.

Figures 6 and 7 show the invention applied to a two way switch.

Figure 8 is a detached view of a switch unit.

Figure 9 is a section and Figure 10 a plan showing the carrier applied to a wire fuse,

Figures 11 and 12 are similar views showing a carrier containing a number of fuse wires, and Figures 13 and 14 are plans showing the cut-outs with a number of mercury columns arranged in parallel.

Referring to Figures 1 and 2 the carrier comprises two metal portions A B placed end to end and separated from one another by a disc C of mica or other insulating material. The portion A has a hole a to receive

the core D which is constructed from silica, ganister, fire clay, or other suitable refractory insulating material. The core is enclosed in a metal tube or casing d and is formed with a passage d¹ for a column of

mercury. A portion d² of this passage is restricted and the length, diameter and position of this restricted passage determine the amperage at which the column will part. The restricted passage can moreover be

placed at a point in the column which will enable the apparatus to be used either on

alternating, or direct current. The top of the metal casing or tube is formed with one or more ears d³ (Figure 3) to facilitate the removal of the core from the carrier. That is when the cap A¹ or cover A¹ is removed the upwardly projecting ears d³ may be grasped by pliers and thereby the core withdrawn. Projecting from a cover A¹ on the portion A is a contact blade a¹ adapted to be pivoted to a spring contact on an insulated base and to be retained in a tilted position by a spring catch M engaging a cam m until such cam is released by raising an insulated handle m¹. The lower end of the portion A is threaded at a² to receive a screwed cap a³ having a cylindrical outer surface. Before this cap is screwed onto the threaded portion a², a mica or other insulating ring C¹ is pushed over the threaded portion and such ring is followed by a flanged mica or other insulating ring C². The upper end of the lower metal portion B is made the same diameter as the outer diameter of the cap a³ and interposed between these parts is the aforesaid disc C of mica, or other insulating material. The portion B constitutes a cup having a bore b the same diameter as the bore at the lower end of the portion A and inserted in this cup is a mica or other insulating tube C³ which overlaps the lower end of the core D and abuts against an asbestos or other washer d⁴ which is placed between such end and a shoulder d⁴ on the core. Projecting from the bottom of the cup is a copper, or other appropriate metal stud of which one portion b¹ forms a fluid tight joint with the tube C³ and another portion b² is reduced in diameter to leave an annular space d⁵ around it for the passage of mercury. The upper end of the stud is again reduced in diameter to enter a hole d⁶ at the bottom of the core.

The outer surface of the reduced portion or portions of the stud are serrated, or otherwise formed to afford a large surface contact when surrounded by mercury. The portion B is reduced in diameter at b³ to form a shoulder b⁴ and projecting laterally from the portion B is a contact blade b⁵ adapted to engage spring contacts on an insulating base until the carrier is tilted to disengage b⁵ from the spring contacts and engage the stepped portion of the cam m with the catch M. The portions A and B are connected together by a sleeve F divided longitudinally and formed with an internal flange f at one end

to engage the flanged ring C^2 and an external screw thread f^1 at the other end to receive a union nut f^2 . Before the sleeve and nut are placed in position, a mica or 5 other insulating tube C^4 is passed over the cap a^3 and the upper end of the portion B, and a flanged mica or other insulating ring C^5 is passed over the portion b^3 . The nut f^2 is then screwed up and the two portions 10 of the sleeve are clamped together by screws f^3 (Figure 4). Situated at one side of the sleeve is a handle F^1 which may be constructed from any suitable insulating material and be supported by arms f^4 projecting 15 from the sleeve. The handle may also be insulated from such arms by an insulating shield C^6 . The construction described affords very high insulation between the top and bottom contacts and between the handle 20 and the carrier. The top of the carrier is provided with a lid or cover A^1 that is secured to the carrier by screws a^4 . In the example shown in Figure 1 a copper or 25 other suitable tube a^5 is fixed in the lid and enters the upper end of the core D to make good surface contact the internal diameter of the tube being the same as that of the core at this point. A portion of the lid is 30 hollowed out at a^6 to form a curved deflecting surface to deflect the mercury into the well a^7 . Surrounding the tube a^5 is a 35 washer a^8 and interposed between the latter and the core is an asbestos or other packing ring a^9 . Both the washer a^8 and the tube a^5 are partly cut away at a^{10} to form a continuation of the well a^7 . The washer a^8 is 40 forced down onto the top of the core to press the latter firmly onto the asbestos or other packing d^x between the core and the 45 mica tube C^3 . For this purpose a plate a^{11} has two or more pins a^{12} which pass through holes in the lid or cover and bear on the top of the washer a^8 . Pressure is exerted on such plate by means of a central screw a^{13} 50 passing through a bridge piece a^{14} on the cover. The latter is provided with a filling aperture a^{15} normally closed by a screw stopper a^{16} which also acts as a valve for preventing escape of mercury when the apparatus 55 is in transit, or not in ordinary use. In the wall surrounding the filling aperture are one or more air vents a^{17} to allow free escape of gas produced by vaporization of the mercury. The front of the well is fitted 60 with a window or lens a^x to show whether the mercury has been discharged into the well or whether it is still in the column. In addition to the window the apparatus may be fitted with an alarm sounding device to indicate when the circuit is broken. This is effected in the example shown by a 65 screwed metal rod E passing through a vulcanite bush e and provided with a lock nut e^1 and a clamping nut e^2 between which a wire e^3 leading to a bell and battery is

fixed. This rod can be adjusted to any height above the surplus mercury in the well so that it will make contact when the mercury column parts and flows over into the well.

70

In the cut-out or circuit breaker shown in Figures 4 and 5 the upper contact a^{18} comprises a copper or other suitable block that is placed at the side of the core D and communicates with the passage d^1 through a 75 branch passage d^7 . The contact a^{18} is recessed at a^{19} and such recessed portion is serrated or otherwise formed to make good surface contact with the mercury. The contact is maintained in position against the core and carrier by suitable screws. In the embodiment illustrated in Figs. 4 and 5 two such screws a^{20} are provided for this purpose.

80

However, a single screw a^{200} , extending 85 through the blade a^1 , may be employed as shown in Fig. 5a. In this example the core is pressed firmly onto the washer d^x above the mica tube C^3 by a plate a^{21} and central screw a^{22} . The plate is hollowed out at a^{23} 90 to form a curved deflecting surface for directing the mercury from the column to the well and an asbestos or other washer a^8 is interposed between the plate a^{21} and the top of the core.

95

In the example shown in Figures 6 to 8 the lower contact blade b^5 of each switch unit is pivoted in a spring contact L on an insulating base l of the switch and the upper contact blade a^1 of each switch unit is 100 adapted to engage and disengage a spring contact L^1 on the base l. The contact blade a^1 is connected by a link l^1 to an arm l^2 on a shaft l^3 that is provided outside the switch casing with an insulating handle l^4 . 105 l^5 indicates a spring for preventing the arms l^2 knocking against the casing l^6 when the switch is pulled out. d^8 indicates a packing of asbestos wool, or other suitable material for preventing injury to the core D by the 110 shock that is set up by the usual switch spring which is coiled round the sleeve on the shaft and is connected to such sleeve and the casing or other fixed part. This spring throws the arms l^2 out immediately 115 the handle l^4 has been moved far enough to disengage, or nearly disengage the top contacts a^1 from the spring contacts L^1 . The filling aperture a^{15} is provided with a ball a^{24} and spring a^{25} which closes such aperture 120 when the switch is opened. When the switch is closed the ball travels under an abutment l^8 so that gas can escape through the filling aperture in the event of the mercury in the 125 column vaporizing. For transit, or other purposes the switch lever l^4 is held partly out by a screw l^9 and in this position the ball a^{24} clears the abutment l^8 and remains closed. When the switch has been duly fixed and connected up the screw l^9 is removed and the 130

apparatus is then ready for work. The switch unit shown in Figure 8 is provided with a tubular contact a^5 in a similar manner to that described in Figure 1 but it may, if desired be provided with a side contact and branch passage similar to the one shown in Figure 4. In any of the arrangements described a number of mercury columns may be arranged in parallel and discharge separately into a well or overflow, or a series of such as shown in Figures 13 and 14.

Referring to Figures 9 and 10, D^x indicates a fire-clay or other suitable core that is formed with a combustion chamber D^1 and with a passage D^2 for the wire N . This core is enclosed in a carrier comprising two metal portions A and B placed end to end and separated from one another by a disc C of mica, or other insulating material. The two metal portions are connected together by a longitudinally divided sleeve F that is insulated from the portions A and B by mica, or other insulating rings C^2 , C^4 and C^5 . a^1 indicates the top contact and b^5 the bottom contact. These contacts fit on circular portions of A and B and are detachably connected therewith by set screws a^{20} , or other suitable means. The wire N is attached to terminals n , n^1 on the top and bottom contacts. The modification shown in Figures 11 and 12 is the same as that described with reference to Figures 9 and 10 with the exception that the core is formed with a number of passages D^2 to receive a number of wires M arranged in parallel. In this construction the core is advantageously made in two portions divided longitudinally. The construction described in addition to affording great mechanical strength and high insulation also provides free ventilation and room for escape of gas.

What I claim as my invention and desire to secure by Letters Patent in the United States is:—

1. In an electrical cut-out, the combination of a tubular core of insulating material, two metal carrier portions encasing said core, insulating material preferably mica separating and insulating said carrier portions from one another, a metal sleeve encircling said carrier portions and securing same together and insulating material preferably mica interposed between the sleeve and the carrier portions and insulating the sleeve therefrom.

2. In an electrical cut-out, the combination of a tubular core of insulating material, two metal carrier portions encasing said core, means situated within the core for making an electrical connection between said portions, means situated outside the core for separating and electrically insulating said carrier portions from one another, a metal sleeve encircling said carrier portions and securing same together and means for

electrically insulating the metal sleeve from the carrier portions.

3. In an electrical cut-out, the combination of a tubular core of insulating material, two metal carrier portions encasing said core, means situated within the core for making an electrical connection between said portions, means situated outside the core for separating and electrically insulating said carrier portions from one another, an internally flanged longitudinally divided metal sleeve encircling said carrier portions and securing same together, means for electrically insulating the sleeve from the carrier portions and means for connecting the two portions of the sleeve together.

4. In an electrical cut-out, the combination of a core of insulating material, the said core having a longitudinal passage for a column of mercury restricted for a portion of its length at some predetermined point below the top of the core, a metal sheath enclosing said core tightly and formed at its upper end with a projecting surface, two metal carrier portions encasing said core, means for electrically insulating said carrier portions from one another, a metal sleeve encircling said carrier portions and securing same, means for electrically insulating the metal sleeve from the carrier portions, an overflow situated in the upper metal carrier portion at one side of the core, a metal cover attached to the top of the upper metal carrier portion and having a passage leading from the top of the core passage to the overflow and means for making a fluid tight joint at the ends of the core.

5. In an electrical cut-out, the combination of a core of insulating material, the said core having a longitudinal passage for a column of mercury, restricted for a portion of its length at some predetermined point below the top of the core, a metal sheath enclosing said core tightly and formed at its upper end with a projecting surface, two metal carrier portions encasing said core, means for electrically insulating said carrier portions from one another, a metal sleeve encircling said carrier portions and securing same, means for electrically insulating the metal sleeve from the carrier portions, an overflow situated in the upper metal carrier portion at one side of the core, a metal cover attached to the top of the upper metal carrier portion and having a passage leading from the top of the core passage to the overflow, a regulating screw mounted on the top of the cover, a plate engaged by said screw and having pins passing through apertures in the cover a metal plate mounted above the core and engaged by said pins, a packing interposed between said plate and the core and another packing interposed between the bottom of the core and its seating.

6. In an electrical cut-out, the combina-

- tion of a core of insulating material, the said core having a longitudinal passage for a column of mercury, restricted for a portion of its length at some predetermined point below the top of the core, a metal sheath enclosing said core tightly and formed at its upper end with a projecting surface, two metal carrier portions encasing said core, means for electrically insulating said carrier portions from one another, a metal sleeve encircling said carrier portions and securing same, means for electrically insulating the metal sleeve from the carrier portions, an over-flow situated in the upper metal carrier portion at one side of the core, a metal cover attached to the top of the upper metal carrier portion and having a passage leading from the top of the core passage to the overflow, a filling aperture formed in the cover above the overflow a valve mounted in said filling aperture and a vent for putting the overflow in communication with the atmosphere when the valve is open.
7. In an electrical cut-out, the combination of a core of insulating material, the said core having a longitudinal passage for a column of mercury, restricted for a portion of its length at some predetermined point below the top of the core, a metal sheath enclosing said core tightly and formed at its upper end with a projecting surface, two metal carrier portions encasing said core, means for electrically insulating said carrier portions from one another, a metal sleeve encircling said carrier portions and securing same, means for electrically insulating the metal sleeve from the carrier portions, an overflow situated in the upper metal carrier portion at one side of the core, a metal cover attached to the top of the upper metal carrier portion and having a passage leading from the top of the core passage to the overflow, a filling aperture formed in the cover above the overflow, a valve mounted in said
- filling aperture, a vent for putting the overflow in communication with the atmosphere when the valve is open and a window situated at the front of the overflow for inspection purposes.
8. In an electrical cut-out, the combination of two metal carrier portions adapted to contain a tubular core, insulating material preferably mica separating and insulating said carrier portions from one another, a metal sleeve encircling said carrier portions and securing same together and insulating material preferably mica interposed between the sleeve and the carrier portions and insulating the sleeve therefrom.
9. In an electrical cut-out the combination of a core of insulating material, the said core having a longitudinal passage for a column of mercury restricted for a portion of its length at some predetermined point below the top of the core, a branch passage communicating with the upper part of the longitudinal passage, an upper metal carrier portion encasing said core and having an overflow chamber at one side thereof and a recess at the other side of the core, opposite to the overflow, a contact block preferably copper situated in said recess and shaped to fit a portion of the core, the said contact block having a serrated recess communicating with the branch passage, means actuated from the exterior of the carrier for forcing the contact block against the core and onto the bottom of the recess, a lower metal carrier portion insulated from the upper metal carrier portion, a metal sleeve encircling said carrier portions and securing same together and means for insulating the sleeve from the carrier portions.
- In testimony whereof I affix my signature in the presence of two witnesses.
